CLAIM

I claim the ornamental design for a combined container and closure, as shown and described.

DESCRIPTION

FIG. 1 is a front perspective view of a combined container and closure in accordance with the present invention.

FIG. 2 is a front elevational view of the combined container and closure in FIG. 1.

FIG. 3 is a top plan view of the combined container and closure of FIGS. 1 and 2.

FIG. 4 is a side elevational view of the combined container and closure of FIGS. 1-3, the opposing side elevational view being a mirror image of FIG. 4.

FIG. 5 is a rear elevational view of the combined container and closure of FIGS. 1-4.

FIG. 6 is a bottom plan view of the combined container and closure of FIGS. 1-5; and,

FIG. 7 is a front perspective view of the combined container and closure, with the closure portion having been removed for clarity of illustration.
